Primary Examiner — Cynthia Ramirez*Assistant Examiner* — Jeremy S. Swartz(74) *Attorney, Agent, or Firm* — Jeenam Park(57) **CLAIM**

The ornamental design for a bunk bed, as shown and described.

DESCRIPTION

FIG. 1 is a front, top and left side perspective view of a bunk bed, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged view of a portion of the bunk bed marked in FIG. 1. The broken lines in FIG. 1 demarcate enlarged areas and form no part of the claimed design.

1 Claim, 8 Drawing Sheets(56)
